UNITED STATES PATENT OFFICE.

FRANK SIKORA, OF PHILADELPHIA, PENNSYLVANIA.

MACHINE FOR DYEING STOCKINGS OR THE LIKE.

1,301,184.

Specification of Letters Patent. Patented Apr. 22, 1919.

Application filed March 27, 1918. Serial No. 225,001.

To all whom it may concern:

Be it known that I, FRANK SIKORA, a citizen of the United States, residing at Philadelphia, in the county of Philadelphia and State of Pennsylvania, have invented certain new and useful Improvements in Machines for Dyeing Stockings or the like, of which the following is a specification.

My invention relates to a machine for dyeing stockings and other articles of apparel while not necessarily restricted to this use.

An important object of the invention is to provide a machine of the above mentioned character, which is simple in construction, inexpensive to manufacture, and will effect a substantial saving in the use of liquid dyes and labor.

Other objects and advantages of the invention will be apparent during the course of the following description.

In the accompanying drawings forming a part of this specification and in which like numerals are employed to designate like parts throughout the same,

Figure 1 is a side elevation of apparatus embodying my invention,

Fig. 2 is a plan view of the same,

Fig. 3 is a central vertical longitudinal sectional view through the same,

Fig. 4 is a transverse section taken on line 4—4 of Fig. 1, and,

Fig. 5 is a similar view taken on line 5—5 of Fig. 1.

In the drawings, wherein for the purpose of illustration is shown a preferred embodiment of my invention, the numeral 5 designates a base or foundation, upon which are rigidly secured uprights or vertical beams 6, connected at their upper ends by a transverse member 7. Connected with the upper ends of the beams 6 are horizontal rods or bars 8, extending downwardly in the form of vertical guide bars 9, having coacting vertical guide bars 10, arranged near and spaced therefrom. The bars 9 and 10 are rigidly attached at their lower ends with the base 5. Connected with the upper ends of the uprights 6 are pairs of spaced longitudinally curved guide rods 11, having longitudinal openings 12 therebetween. These guide rods constitute guides or tracks, as shown. The lower ends of the pairs of guide rods 11 are rigidly attached to a stationary outer tank or receptacle 13, having legs or supports 14, rigidly attached to the base 5, as shown.

The numeral 15 designates a vertically

swinging inner tank or receptacle, adapted for movement into and out of the stationary tank 13 and being perforated, as shown. The inner tank or receptacle 15 is provided upon its sides and its forward end with apertured ears 16, receiving pivots 17, secured to the uprights 6. The pivots 17 are arranged at the upper end or top of the perforated tank 15 and the longitudinally curved guide rods 11 are concentric with the pivots 17. Near the opposite or outer end of the perforated tank 15, and at the top thereof, the same is provided with laterally extending pins or elements 18, operating within the longitudinally curved openings 12 between the guide rods 11.

Cables or flexible elements 19 are attached to the top of the perforated trough 15, near its outer side, as shown at 20, and these cables pass about grooved pulleys 21, rotatable within brackets 22, secured to the uprights 6, near the upper ends thereof. The cables 19 are further passed about grooved pulleys 23, pivoted upon horizontal bars 24, attached to the upper ends of the rods or bars 9 and 10. The cables 19 have their free ends connected with weights 25, provided in their ends with openings for slidably receiving the guide rods 9 and 10. These weights are adapted to substantially balance the weight of the perforated tank 15, but the perforated tank is slightly heavier than these weights so that it will gravitate to the lower position, when released.

Means are provided to raise the perforated tank 15, comprising a cable or flexible element 26, attached to the outer end of the perforated tank 15 between the sides thereof, as shown at 27. The cable 26 is passed about a grooved pulley 28, which is pivoted upon a shaft 29. This shaft 29 carries the pulleys 21 and has its ends journaled in the brackets 22. The cable 26 extends downwardly over this pulley for connection with a hoist or winch 30, embodying a rotatable drum 31, shown as rotated by a hand crank 32, while the same may be turned by any other suitable means.

When in the elevated position, the perforated tank 15 is adapted to discharge or dump the stockings or the like into an inclined trough, chute or receptacle 33 extending downwardly toward or into the outer tank 13, to conduct the liquid dye back into the same. At the forward or upper end of the trough or chute 33, I provide a wringing

mechanism embodying a pair of rolls 34, between which the stockings are passed for wringing the same.

The stockings, when passing through the 5 wringer, discharge into a preferably perforated removable tank or receptacle 35, inserted within stationary rinsing tank or receptacle 36, supported by legs 37, fixed to the base 5.

- 10 The vertically swinging perforated tank 15 has its sides apertured near their tops, for pivotally receiving a transverse rotatable shaft 38, having a rotatable agitator 39 rigidly secured thereto. This agitator operates 15 within the upper portion of the perforated tank 15, as shown. Rigidly connected with one end of the shaft 38 is a gear 40, contacting with a lower gear 41, rigidly secured to a stub shaft 42. This stub shaft is attached 20 to the tank 13. The stub shaft 42 has a sprocket wheel 43 rigidly secured thereto, for rotating it. It is thus seen that the gears 40 and 41 being free to disengage upon the upward movement of the perforated tank 25 15, these gears in no way interfere with such movement of the perforated tank, the shaft 38 being disposed above the top of the tank 13.

The sprocket wheel 43 is engaged by a 30 sprocket chain 44, engaging a sprocket wheel 45. The sprocket wheel 45 is rigidly secured to a stub shaft 46, having a sprocket wheel 47 rigidly attached thereto. This stub shaft 46 is rotatably connected with the upright 6. 35 The sprocket wheel 47 is engaged by a sprocket chain 48, extending forwardly to engage a sprocket wheel 49, rigidly connected with the upper roll 34, to drive the same in the direction of the arrow, as shown in 40 Fig. 2. The shaft 42 is preferably equipped with a pulley 50, whereby the shaft may be driven by any suitable means.

The operation of the apparatus is as follows:

- 45 The liquid dye is placed within the tanks 13 and 15, the tank 15 being in the lower or inner position. The stockings or the like are then introduced into the tank 15. The shaft 42 is rotated and this rotation is imparted to 50 the agitator 39, and the wringing mechanism is also operated. After the stockings have remained in the liquid dye for a suitable period, the hoisting mechanism 30 is operated to elevate the perforated tank 15, the 55 same subsequently swinging to the lower position when released. In this elevated position, the perforated tank 15 discharges or dumps the stockings saturated with the liquid dye upon the inclined trough or chute 33. These stockings are then passed through 60 or between the rollers 34 of the wringing mechanism, the stockings discharging into the tank 35, while the liquid dye gravitates rearwardly through the trough 33 and is 65 thereby returned into the tanks 13 and 15,

to be again used. Within the tanks 35 and 36, the stockings are rinsed, such as with plain water. The perforated inner tank 35 may now be removed and the stockings may be dumped into a truck or the like so that 70 the rinse water will drain therefrom.

It is to be understood that the form of my invention herewith shown and described is to be taken as a preferred example of the same, and that various changes in the shape, 75 size, and arrangement of parts may be resorted to without departing from the spirit of the invention or the scope of the subjoined claims.

Having thus described my invention, I 80 claim:

1. In apparatus for dyeing stockings or the like, a relatively stationary tank, a perforated tank adapted for insertion within the stationary tank and pivotally supported 85 near one end to be swung upwardly for assuming an elevated position, and a trough arranged near the pivoted end of the perforated tank to receive the stockings or the like therefrom and adapted to return the 90 liquid to the stationary tank.

2. In apparatus for dyeing stockings or the like, a relatively stationary tank, a foraminous inner tank arranged therein, means for pivotally supporting the inner tank, a 95 receptacle arranged in coöperative relation to the stationary tank and adapted to receive the stockings and liquid dye from the inner tank when it is swung upon its pivot and to hold liquid dye so that it is not 100 wasted, said receptacle having means of communication with the stationary tank to return the liquid dye to the stationary tank, and means to swing the inner tank upon its pivot. 105

3. In apparatus for dyeing stockings and the like, a relatively stationary tank, an inner foraminous tank movable into and out of the stationary tank and having one end thereof pivotally supported, a receptacle to 110 receive the stockings and liquid discharged from the lower end of the foraminous tank when it is elevated, means to elevate the opposite end of the foraminous tank, a movable agitator carried by and arranged with 115 in the foraminous tank, and means to drive the agitator when the foraminous tank is in the lowered position.

4. In apparatus for dyeing stockings and the like, a relatively stationary tank, an inner foraminous tank movable into and out of the stationary tank and having one end thereof pivotally supported, a receptacle to receive the stockings and liquid discharged from the lower end of the foraminous tank 120 when it is elevated, means to elevate the opposite end of the foraminous tank, a rotatable agitator arranged within and permanently secured to the foraminous tank, a gear connected with the agitator to rotate 125 130

the same, a gear secured to the stationary tank and adapted to engage with the first named gear when the foraminous tank is lowered, and means to drive the gear on the 5 tank.

5. In apparatus for dyeing stockings and the like, a relatively stationary tank, an inclined trough arranged near one end of the tank and discharging into the same, an apertured inner tank adapted for movement into and out of the outer tank and pivotally supported at one end near the trough to discharge into the trough when its opposite end is elevated, a curved track arranged near 10 the opposite end of the outer tank and extending above the same, a guide element secured to the corresponding end of the inner perforated tank and engaging the guide element, and means to raise the free end of the 15 inner tank.

6. In apparatus for dyeing stockings and the like, a relatively stationary tank, an inclined trough arranged near one end of the tank and discharging into the same, an apertured inner tank adapted for movement into and out of the outer tank and pivotally supported at one end near the trough to discharge into the trough when its opposite end is elevated, a curved track arranged near the 20 opposite end of the outer tank and extending above the same, a guide element secured to the free end of the inner perforated tank and engaging the guide element, a counterweight connected with the free end of the 25 inner tank, and separate means for raising the free end of the inner tank.

7. In apparatus for dyeing stockings or the like, a relatively stationary tank, a foraminous tank adapted for movement into 30 and out of the stationary tank, means to move the foraminous tank out of the stationary tank, a movable agitator arranged within the foraminous tank and permanently 35

secured thereto, a gear connected with the agitator to drive it, a second gear secured to 45 the stationary tank and adapted to engage with the first named gear when the foraminous tank is in the lower position, and means to drive the second named gear.

8. In apparatus for dyeing stockings or the like, a relatively stationary tank, a foraminous inner tank adapted for movement into and out of the stationary tank, means to elevate the inner tank with relation to the stationary tank, a transverse shaft connected 55 with the inner tank, a rotatable agitator carried by the transverse shaft and arranged within the inner tank, a gear secured to the transverse shaft, a second gear secured to the stationary tank to engage with the first 60 named gear when the inner tank is lowered, and means to drive the second named gear.

9. In apparatus for dyeing stockings or the like, a relatively stationary tank, a foraminous inner tank adapted for movement 65 into and out of the stationary tank, means to elevate the inner tank with relation to the stationary tank, and a movable agitator arranged within the inner tank and permanently carried thereby. 70

10. In apparatus for dyeing stockings or the like, a relatively stationary tank, a foraminous inner tank arranged within the stationary tank, a receptacle arranged in co-operative relation to the stationary tank and 75 having means of communication therewith to return liquid into the same, and means to elevate the inner tank with relation to the stationary tank and dump the contents of the same into the receptacle. 80

In testimony whereof I affix my signature in presence of two witnesses.

FRANK SIKORA.
